UNITED STATES PATENT OFFICE.

CHARLES R. BUTTON, OF WORCESTER, MASSACHUSETTS.

GRINDER.

1,087,527.

Specification of Letters Patent. Patented Feb. 17, 1914.

Application filed March 8, 1913. Serial No. 752,821.

To all whom it may concern:

Be it known that I, CHARLES R. BUTTON, a citizen of the United States, residing at Worcester, in the county of Worcester and 5 State of Massachusetts, have invented a new and useful Grinder, of which the following is a specification.

This invention relates to a domestic grinding machine and the principal objects there- 10 of are to provide a grinder of simple and inexpensive construction suitable for use in an ordinary kitchen and capable of universal use for the grinding of practically all kinds of kitchen utensils, whether large or small; 15 and in which the tool can be held firmly in any desired position relative to the grinding wheel; in which the grinding wheel can be caused to move longitudinally of the work; in which the mechanism for producing the 20 longitudinal motion can be thrown out of operation so as to permit the operator to move the blade along the wheel instead of having the wheel move along the blade; in which the blade will be held firmly and se- 25 curely and can be adjusted to any desired angle with respect to the wheel so as to pro- 30 vide for grinding a blade in which the edge makes an angle to the back; also to provide a simple and effective device for moving the 35 blade along the wheel by hand, either par- 40 allel with the stone or at an angle thereto; to provide a simple arrangement by which the blade can be turned through small angles automatically merely by moving the blade 45 holder longitudinally; and to provide an 50 improved form of brackets for holding the blade holder and an improved form of blade 55 holder.

Further objects and advantages of the in- 60 vention will appear hereinafter.

Reference is to be had to the accompany- 65 ing drawings in which,

Figure 1 is a plan of a preferred embodiment of the invention showing it in opera- 70 tion; Fig. 2 is a similar plan of a part of the mechanism showing one way in which the mechanism can be adjusted; Fig. 3 is a 75 transverse sectional view on the line 3—3 of Fig. 1; and Fig. 4 is an end view showing 80 the parts in another adjusted position.

The invention is shown in the form of a 85 simple machine embodying a main frame 10 having a bracket 11 and bolt 12 for securing 90 it to a table, window sill or the like. On 95 this frame are end pieces 13 provided with

screws 14 extending inwardly from the out- 60 side and adjustably fixed to the end by nuts 15. On these screws is supported a main square shaft 16 having holes in the end for receiving the screws. It will be seen, there- 65 fore, that the shaft is readily dismountable and that the screw can be adjusted to take up wear, and that when adjusted the screws are stationary and the shaft turns upon them.

The shaft is provided with a pinion 17 designed to be operated by a gear 18 having a handle 19 and mounted to turn on an ex- 70 tension 20 on the frame. A guard 21 is shown for the pinion. On the square shaft 75 16 is the hub 22 of a grinding wheel 23. This hub has a square passage therethrough and the wheel is free to move along the shaft and of course turns with it. The hub is provided with a circumferential groove 24.

Mounted on the end pieces in a way similar 80 to that described for the shaft 16, is a screw- threaded shaft 25. Means is provided for transmitting motion of rotation from the shaft 16 to the shaft 25. This means is 85 capable of being readily disconnected and is shown in the present instance as comprising two grooved pulleys 26 and 27, one on each shaft, and a belt 28 for connecting them. The screw-threaded shaft 25 is provided 90 with a nut 29 which has a yoke 30 extending into the groove 24 of the hub 22.

The operation of the parts so far de- 95 scribed will be obvious. The rotation of the gear 18 rotates the shaft 16 at a high speed and also the shaft 25 when the belt is in position. This causes the wheel 23 to rotate at a rapid rate and causes it to travel back and forth along the shaft so as to traverse a blade from end to end.

For the purpose of supporting the blade 100 the following devices are shown: On the back of the frame 10 are a pair of integral upward projections 35 to each of which is pivoted an arm 36, this arm being free to swing forward and back through a wide arc. On the end of this arm is pivoted a second arm 37, also pivoted to swing through a wide arc. The adjustments of these arms will be indicated in a general way by com- 105 parison of Figs. 3 and 4. The pivot points are made in such a way as to prevent the turning of the arms on any axis except the axes of the pivots. The arms 37 are pro- 110 vided with perforations at 38 through which

freely passes a rod 39, this rod being supported by the two arms. As the two pairs of arms are adjustable independently of each other, the rod can be turned to various positions; that is it can be turned from the position shown in Fig. 1, in which it is parallel with the shafts, to various positions in which it makes an angle to the shafts, as for example that shown in Fig. 2, and one end can be made higher than the other if desired. The rod is provided with a handle 40 for operating it and it is also provided with a guide in the form of a blade 41 having a bottom guiding edge at an angle to the rod 39. This is held on the rod by a nut 42 and can be adjusted to any desired position.

On the rod is a work clamp shown as comprising a lower member 45 having a bottom and integral upwardly extending sides made of sheet metal, and a top part 46 having a top and integral downwardly extending sides fitting between the sides of the member 45 and also made of sheet metal. At the front end these parts are provided with teeth 47 constituting jaws for clamping the work. The sides of the two parts 45 and 46 are provided with registering perforations for the rod 39. At the rear this clamp is provided with a screw 48 and a nut 49 located between the downwardly extending sides of the part 46. The screw extends through openings in the two parts 45 and 46.

In operation the blade to be operated upon is placed between the jaws 47 and the screw 48 tightened up after the blade is adjusted to approximately the right position relatively to the grinding wheel. The tightening of this screw not only tightens the blade in position, but it also exerts controlling pressures on the walls of the passages in the sides of the parts 46 and 45 so as to clamp the work clamp on the rod 39. This having been accomplished, the rod can be adjusted more accurately to the desired position and then the machine operated in any desired way. If the blade to be sharpened is a straight one, the rod is adjusted to the proper position and then the wheel 18 is turned, moving the grinding wheel back and forth along the straight edge of the blade. If it is found that the blade is not in exactly the proper position, it is not necessary to resort to the proper placing of the arms 36 and 37 if they are approximately accurate, as the guide 41 can be tightened up in position to rest on one of the arms 37 and then the rod 39 can be moved longitudinally toward the blade. As the turning of the rod in its own axis is limited by the guide 41 resting on the arm 37 it will be seen that the movement of the rod longitudinally will cause the rod to be turned slightly on account of the incline of the lower surface of this guide. This adjusts the angle of the blade to the grinding wheel accurately and

finely. If the blade of the knife is curved or angular, the operator can operate the handle 40 to turn the blade frame to any desired position. Thus blades of all shapes can be ground with ease and facility. In cases of curved or angular blades, also it is often desirable to dispense with the feed by throwing off the belt 28 and to loosen the guide 41. In this case the operator can simultaneously feed the blade and adjust it to the wheel. It will be seen, therefore, that an exceedingly simple and inexpensive construction is provided and one in which the length of the machine is substantially equal to the length of the longest blade which it is desired to sharpen in spite of the fact that an effective feed is provided; also that the device is capable of almost universal adjustment and a wide range of use in the ordinary kitchen.

Although I have illustrated and described only one form of the invention, I am aware of the fact that many modifications can be made therein by any person skilled in the art without departing from the scope of the invention as expressed in the claims. Therefore, I do not wish to be limited to all the details of construction herein shown and described, but

What I do claim is:—

1. In a grinding device, the combination with a grinding wheel, of a pair of adjustable supports adjacent thereto, a rod carried by said supports and movable longitudinally therein, said rod having a handle for operating it, and a work-holder mounted on said rod and comprising a pair of members each mounted to freely rotate on the rod and having coöperating jaws for engaging the work, and means for simultaneously clamping said jaws on the work and clamping them to said rod whereby the work-holder will move with the rod.

2. In a grinding machine, the combination with a longitudinally movable and rotatable rod, of a pair of jaws each rotatably mounted on the rod and having means for clamping the work between them, and means for simultaneously clamping the jaws upon the work and securing them fixedly to the rod.

3. A work-holder for a grinding machine or the like comprising a rod, a pair of jaws through which the rod passes, said jaws being pivotally mounted on the rod, and a screw for forcing the rear ends of said jaws apart so as to clamp the work between the opposite ends of the jaws and at the same time clamp the jaws to the rod.

4. As an article of manufacture, a work-holder for a grinding machine or the like comprising two sheet metal jaws, one having a bottom and vertical sides, and the other having a top and vertical sides, said sides being provided with perforations in alignment, a rod passing through said perfora-

tions for supporting the work-holder, said members having jaws on one side for coöperating with each other to hold the work and means for clamping the jaws together and 5 tightening the members on the rod.

5. In a grinding machine, the combination with a grinding wheel, of a set of brackets adjacent thereto, a rod supported on said brackets and longitudinally movable relatively thereto, and a work-holder on the rod, each of said brackets comprising a pivoted arm, a second arm freely pivoted to the end of the first arm and having means for supporting the rod, said arms being adjustable 10 about their pivots independently of each other, whereby the angle and position of the rod can be varied within wide limits.

6. In a grinding machine, the combination of a grinding wheel, a pair of arms pivoted 20 to swing on axes parallel with the axis of the wheel, a second pair of arms each pivoted on one of the arms on a parallel axis, the second arms being perforated and a rod supported in the perforations, and capable 25 of moving longitudinally therein, for supporting the work.

7. In a grinder, the combination with a pair of adjustable supports having circular 30 perforations in their ends adapted to be arranged in alinement with each other, a cylindrical rod passing freely through said perforations, a pair of work-holding jaws of said rod, and a guide on said rod for engaging one of said brackets.

35 8. In a grinding machine, the combination with a grinding wheel, of a longitudinally movable rod adjacent thereto, a work-holder on the rod, and means whereby when the rod is moved longitudinally the angle of the 40 work-holder with respect to the wheel will be changed.

9. In a grinding machine, the combination of a pair of adjustable brackets, a rod rotatably supported by said brackets and movable 45 longitudinally, a pair of jaws mounted on said rod and movable therewith, and a guide projecting from one end of the rod and adapted to engage one of said brackets and having a guiding surface at an angle to 50 the rod, whereby as the rod moves longitudi-

nally it will be caused to turn about said guide.

10. In a grinding machine, the combination of a frame, a pair of adjustable brackets carried by said frame, a rod supported 55 by said brackets and movable longitudinally thereon, a work-holder carried by the rod, a rotatable shaft adjacent to the brackets, a grinding wheel mounted to rotate with said shaft and capable of moving therewith, 60 means for rotating said shaft, and means operated by said shaft for moving the grinding wheel therealong.

11. In a grinder, the combination with a longitudinally movable rod, of a work-holder carried by the rod, means for adjustably supporting the rod, a grinding wheel, and means for simultaneously turning the 65 grinding wheel on its axis and moving it longitudinally with respect to its axis. 70

12. In a grinding machine, the combination of a shaft, a grinding wheel mounted on the shaft to rotate therewith and capable of moving therealong, said grinding wheel having a grooved collar thereon, a screw-threaded shaft parallel with the first shaft, means for rotating the screw-threaded shaft from the first named shaft, and a yoke engaging the grooved collar and having a nut fitting the screw-threaded shaft so as to 80 move therealong. 75

13. In a grinding machine, the combination of a frame a square shaft mounted thereon, a grinding wheel mounted on the square shaft and having a grooved collar, 85 means for rotating the square shaft, a screw threaded shaft parallel with the square shaft above said frame, means for rotating the screw-threaded shaft from the square shaft, a nut on the square shaft, and a yoke 90 extending from said nut and embracing said grooved collar for moving the grinding wheel along the square shaft as it rotates. 90

In testimony whereof I have hereunto set my hand, in the presence of two subscribing 95 witnesses.
